UNITED STATES PATENT OFFICE.

EDWARD H. McCLOUD, OF COLUMBUS, OHIO, ASSIGNOR TO THE KINNEAR MANUFACTURING COMPANY, OF COLUMBUS, OHIO, A CORPORATION OF WEST VIRGINIA.

LOCKING AND RELEASING DEVICE FOR FIRE-SHUTTERS.

1,216,822.

Specification of Letters Patent. Patented Feb. 20, 1917.

Application filed April 8, 1912. Serial No. 688,163.

To all whom it may concern:

Be it known that I, EDWARD H. McCLOUD, a citizen of the United States, residing at Columbus, in the county of Franklin and 5 State of Ohio, have invented a certain new and useful Improvement in Locking and Releasing Devices for Fire-Shutters, of which the following is a specification.

The chief object of this invention is to 10 provide improved means for facilitating the testing of a normally thermally controlled rolling fire shutter so that it can be manually released and recoiled from the interior of a building.

15 The invention is embodied in the example herein shown and described, the features of novelty being pointed out in the claim.

In the accompanying drawing forming part hereof—

20 Figure 1 is a view in end elevation showing the devices in position for locking the shaft of the shutter roller.

Fig. 2 is a similar view showing the devices in roller releasing position.

25 Fig. 3 is a detail in elevation showing the handle at the interior of the building controlling the locking and releasing devices at the exterior of the building.

Fig. 4 is a front view of that end of the 30 rolling shutter containing my invention.

The invention is more especially adapted for use in connection with what are called normally unbalanced coiling shutters, that is the species in which the flexible shutter is 35 normally held coiled up and is liberated automatically by a dangerous rise of temperature for uncoiling mainly by gravity in the event of fire. It will be understood by those skilled in the art that 6 represents one of a 40 pair of end brackets to support such a shutter and that 5 is the end of a roller shaft supported between such a pair of brackets. 7 represents a wall to the outer side of which the brackets are secured. The shaft 7 has 45 secured to it a spur or ratchet wheel 8. Fulcrumed on a pin 9 projecting from the side of the bracket is a lever 10 which extends under the wheel. Pivoted on the lever near its middle is a pawl 11 having its lower end 50 weighted so as to cause its tooth-end to normally point toward the wheel 8. On the free end of the lever 10 is a small anti-friction roller 12. Pivoted on a short stud 13 on the bracket above the free end of the lever 10

is a second lever 14 having a bearing edge 55 14^a for the anti-friction roller 12, and an edge 14^b that contacts with the lower edge of the lever 10 and, in conjunction with a curved socket 14^c, limits the upward movement of the two levers when the lever 14 is 60 caused to actuate the lever 10. The lower end of the pawl 11 oscillates in a socket 14^d in the lever 14.

The lever 14 has connected to its free end a chain 15 containing a fusible link 15^a said 65 chain being extended into hole 7^a in the wall 7 of the building toward the interior thereof and said chain having attached to its inner or free end a handle composed of two parts 16 and 16^a jointed together by a hinge joint 70 at 17. Secured by bolts 19^a on the inner side of the wall 7 at the inner end of the hole 7^a is a plate or escutcheon 18 having an opening for the handle 16—16^a. Said plate has on its inner side a thimble 18^a extending 75 into the hole 7^a. On the outer side of the plate 18 at its opening is a curved guard flange 18^b and below said flange a hook 19 in vertical line with said opening. The hook is open at one side and the flange 18 at the 80 corresponding side is inclined away so that the handle after flexion downward can be swung in a vertical plane into and out of the hook as seen by full and broken lines Fig. 3. When the handle hangs vertically 85 and is within the hook 19 it and the chain as well as the devices at the exterior (except the pawl and roller) are locked from movement. To release the devices at the exterior the handle is first swung to the broken line 90 position Fig. 3 and then raised to horizontally aline with the hole in the wall when the weight of the levers 10 and 14 will cause the said levers to fall away to the position shown in Fig. 2. The chain 15 is, of course, 95 made of such length that when the pawl 11 is drawn up to ratchet-engaging position, or as shown in Fig. 1, the handle part 16 can be turned down into the hook on the plate as seen in Figs. 1 and 3. The line 20 designates the plane of the hanging shutter. It 100 will be clear, therefore, that when the parts are in the position shown in Fig. 1 the shutter can be coiled upon the roller by pushing it up and that as fast as the shutter is pushed 105 up the pawl 11 catches the near tooth of the ratchet wheel and holds the shutter from uncoiling.

The operation is therefore readily understood. To cause the uncoiling of the shutter it is only necessary to turn the handle 16 from the position shown in Fig. 1 to horizontal position when the parts will promptly assume the position seen in Fig. 2 after which the shutter will drop by gravity. A shoulder 16^b on the handle serves as a stop to prevent the handle from passing too far into the hole 7^a when the shutter is released. To restore the shutter to coiled up condition the parts are replaced to the position shown in Fig. 1 by drawing out the handle part 16 and securing it as before stated, and as shown in full lines Figs. 1 and 3. The bearing edge 14^a when pulled inward on the anti-friction roller 10^a causes the lever 10 to rise. After this operation the shutter is pushed up, the ratchet wheel slipping over and oscillating the pawl. The shutter can be pushed up from the interior of the building, first by raising the lower sash of the window and finally by lowering the two sashes and completing the coiling of the shutter by working it through the opening provided by lowering the two sashes.

It will be observed that this invention makes it especially convenient to test the shutter from time to time as this can be done from the interior of the building and with-

out the necessity of employing ladders to reach high places.

The forms of the parts can be changed without departing from the gist of the invention.

What I claim is:

A locking and releasing means for a fire shutter roller provided with a ratchet, comprising in combination, a lever pivoted near the ratchet, a gravity pawl pivoted on said lever to normally engage said ratchet to permit rotation of the ratchet in one direction and prevent rotation in the other direction, a second lever pivoted to swing under the first mentioned lever, the end of said first mentioned lever adapted to normally rest at its end upon the second mentioned lever near the pivot of the latter, a device connected with the second mentioned lever to actuate the same to raise and lower the first mentioned lever to engage and disengage the pawl from the ratchet, and means whereby said second mentioned lever may be held in raised position to hold the pawl normally engaged with the ratchet, substantially as described.

EDWARD H. McCLOUD.
